[57] CLAIM

The ornamental design for a stand for electronic equipment, as shown and described.

DESCRIPTION

FIG. 1 is a front perspective view of a stand for electronic equipment showing my design;

FIG. 2 is a front elevational thereof;

FIG. 3 is a rear elevational view thereof;

FIG. 4 is a left elevational thereof, the right side elevational view being a mirror copy of this view; and,

FIG. 5 is a top plan view thereof.

1 Claim, 4 Drawing Sheets
